UNITED STATES PATENT OFFICE.

JAMES B. GRANGER AND WILLIAM H. JOHNSON, OF DELHI, NEW YORK.

HAME-FASTENER.

SPECIFICATION forming part of Letters Patent No. 439,502, dated October 28, 1890.

Application filed May 10, 1890. Serial No. 351,274. (No model.)

To all whom it may concern:

Be it known that we, JAMES B. GRANGER and WILLIAM H. JOHNSON, citizens of the United States, residing at Delhi, in the county of Delaware and State of New York, have invented certain new and useful Improvements in Hame-Fasteners; and we do hereby declare the following to be a full, clear, and exact description of the invention, such as will enable others skilled in the art to which it appertains to make and use the same.

Our invention consists in the novel manner of constructing the hame-fastening hook with an abutting and locking-spring tongue, and also in certain other novel features of construction, as will be hereinafter described.

In the accompanying drawings, Figure 1 is a front elevation of a portion of a horse-collar and of hames with our improved fastening applied thereto. Fig. 2 is a perspective view of our hame-fastener separated from one of the hames and connected to the other. Fig. 3 is a perspective view of one part of the improved hook, and Fig. 4 a perspective view of the other part of the same. Fig. 5 is an edge view of one of the links of the hame-connecting chain. Figs. 6 and 7 are perspective views of the two parts of the hook slightly modified in construction.

The improved hame-fastener hereinafter described does not differ in its main functions essentially from the fastening shown in our Letters Patent dated the 8th day of April, 1890, No. 425,080, and therefore it is not necessary here to explain anything more than the new features of construction we have devised.

The upper part A of our new hook is formed with two longitudinal limbs *a b*, branching from a nearly circular connecting or linking eye *c*. The limb *a* is made considerably stouter than the limb *b* in order to bear the strain to which the hook is subjected. The limb *b* is made quite thin and springy, and is tapered slightly toward its free end, and also gradually increased in width so as to extend far enough across to act as an abutment against the upturned portion of the lower part of the hook. This limb by being springy and branching from the nearly circular eye *c* can be readily pressed upward at its free end for the purpose of unfastening the hame by applying the finger to said end and exerting

an upward force against it. The outer end *d* of the branch *a* is curved downwardly and bent around so as to form a hinging bearing 55 for a pivot-connection of the lower part B of the hook. The said lower part B of the hook is connected to the downwardly-curved and narrowed outer end portion *d* of the part A by means of an upwardly and inwardly curved 60 and widened bifurcated inner end portion *f* of said part B and by a transverse hinging pivot-bar *e* (indicated by dotted circle) between the inner sides of the prongs of said portion *f*, as shown in Fig. 3.

The part B is provided at its upper end with a rabbet-shoulder *g*, and thus the spring-abutment branch of the part A has a rest or stop by which its downward movement is limited.

The part A may have its downwardly-curved portion widened, as at *d'*, while the upwardly-curved portion *f* of the part B may be narrowed, as at *f'*, so as to enter between the bifurcated portion *d'*, as illustrated in Figs. 6 75 and 7. In this construction the pivot-connecting means may be formed on part B, as at *e'*.

It is of very considerable advantage with respect to cost of manufacture of the fastening to have the upper part A formed with a stout branch *a* and springy branch *b* and both branches to extend out from a nearly circular linking-eye *c*, as shown, as this construction gives the required elasticity to the branch 85 *b*, and at the same time affords a linking-eye *c* as means of connection to one of the hames. This mode of forming the part A also enables us to make the springy branch with an increased length, and thus to secure from it and 90 the linking-eye *c* increased volume of spring. In fact nearly the entire length of the hook is made elastic below the branch *a* of the part A, and thus while the branch *b* acts perfectly as an abutment-stop, the hook is very easily 95 unfastened when the branch *b* is moved to the slightest extent, with the finger above a horizontal plane.

In connection with the improved hook we use between the ring *h* of one hame and the 100 hook A B a connection C, formed, preferably, of folded or doubled links *g*, made, preferably, of round iron, and in the form represented. A ring or link *h'* is used between the other

- hame and the hook. Any desired number of the links g may be interposed between the hame and the hook, as circumstances require. The chain of links g and the rings or links h h' will be constructed of lengths or sizes to suit different hames, and the doubled links might have division-cuts which would admit of their being opened for the removal or insertion of a link or links.
10. We contemplate using the ordinary buckle-strap and ring-connections between the hames and the fastening-hook, and therefore do not confine our invention to the folded or doubled links g shown.
15. What we claim as our invention is—
1. As an improved article of manufacture, a hame-fastening hook comprising an upper part having a linking-eye c and two longitudinal branches a b , one of said branches
20. having a spring action and constructed and arranged to serve as a locking-abutment, and

a lower part B , pivotally connected to the part A and lying in its closed position longitudinally under the springy abutment branch b , all substantially as described.

2. As an improved article of manufacture, a hame-fastening hook comprising the folded longitudinal parts A B , pivotally connected together, the part A of said hook having branches a b , linking-eye, and one of said branches having a spring action and the other provided with a downwardly-turned end, and the part B of the hook having an upturned end g' , which is shouldered or rabbeted, substantially as described. 35

In testimony whereof we hereunto affix our signatures in presence of two witnesses.

JAMES B. GRANGER.
WILLIAM H. JOHNSON.
